UNITED STATES PATENT OFFICE.

WILHELM GENSECKE, OF HOMBURG VON DER HOHE, GERMANY, ASSIGNOR TO BERLINER ACTIENGESELLSCHAFT FUR EISENGIESSEREI UND MASCHINENFABRIKATION, OF CHARLOTTENBURG, NEAR BERLIN, GERMANY, A COMPANY OF GERMANY.

PISTON DRIVE FOR COMPRESSORS.

Application filed July 30, 1921. Serial No. 488,633.

To all whom it may concern:

Be it known that I, Dr. WILHELM GENSECKE, of Homburg von der Hohe, a citizen of Germany (whose postoffice address is 87 Homburgerstrasse, Homburg v. d. Hohe, Germany), have invented certain new and useful Improvements in Piston Drives for Compressors (for which I have made application for patents in Germany on Dec. 20, 10 1916, and Apr. 10, 1920, on which have been granted, respectively, Patents 302,807 and 337,746; in Sweden on Apr. 15, 1920, and Feb. 4, 1921; in Switzerland May 28, 1920, on which Patent 88,618 has been granted, and 15 Jan. 27, 1921; and in England Jan. 3, 1921, and Feb. 3, 1921), of which the following is a specification.

This invention relates to a piston drive for compressors or a pump, and the said invention consists substantially in the provision of means whereby the drive is effected through the medium of a sliding block or crank slide arranged in the centre of the piston, and in which the sliding block or crank slide 25 is moved by means of an eccentric.

The advantages thereby obtained, consist in the extreme simplicity of the drive and cheapness of production. The invention is more particularly suitable for short stroke 30 compressors running at high speed. It has already been proposed to drive a double compressor by means of a centrally arranged crank slide, but in the known arrangement no eccentric is used, the block of the crank 35 slide being journalled on the crank pin of a strong and uni-laterally mounted disc, the diameter of which is correspondingly larger than the circle described by the crank pin.

In contradistinction to this known arrangement, the eccentric drive according to this invention offers the advantage of an eccentric, supported on both sides by a comparatively weak shaft so that one-sided and unfavorable stresses are obviated, and a 45 better distribution of the masses is possible together with an improved guidance and lubrication of the piston.

In the drawings Figure 1 is a vertical longitudinal section and Figure 2 a horizontal longitudinal section of a double-acting compressor according to the invention.

Figure 3 is a vertical longitudinal section and Figure 4 a vertical longitudinal section seen in an angle of 90° to Figure 3 of a modi-

fied form of a single acting compressor and 55 Figure 5 a plan view of Figure 3.

The drawing, Figs. 1 and 2, illustrates a constructional example for double acting air compressors in which *a* represents a cylinder, and *b* the piston. For admission of the air, 60 the example illustrated shows suction slots *c*, but it is obvious that in their place, other members such as slots, valves, or the like may be employed.

For outlet of the air, automatic valves *d* 65 are provided. In the centre of the piston, a slot is formed within which a block or crank slide *g* is so arranged as to slide up and down. The movement of the block or crank slide is effected through the medium of an 70 eccentric *f* mounted on the shaft *e*.

In addition to compressors for gases and vapors, the invention may be applied to pumps of any kind. The diameter of the piston *b* need, moreover, not be equal on both 75 sides, as illustrated in the particular example, but it may be different thus offering the possibility of a tandem arrangement i. e. compound action.

The Figures 3-5 show a modified form 80 for single acting air compressors. In this modification sufficient piston guidance and lubrication, accompanied by the desired increase in speed, is effected, with still greater simplicity and further reduction in size by 85 making the compressor of the single-acting type and arranging the guide bar for the sliding block, on the non-compressing side of the piston as a guide disc for the piston. In this connection it is particularly advantageous to provide this guide disc with openings, in so far that it serves to propel the lubricating oil spiriting through the openings in the laterally open interior of the piston. In this way, not only the sliding block 95 and eccentric but also the upper piston guide and bearing, are efficiently lubricated, so that it is possible, with such a compressor although single acting, to increase the speed two-fold and even more, to couple it directly 100 with a corresponding high speed prime mover (electromotor, motor car, internal combustion engine and the like) and thus obtain the same output as with the double-acting compressor of Figures 1 and 2, which, 105 however, has one more delivery valve and takes up a greater longitudinal space.

The drawing shows, in Figures 3-5, a

- small vertical compressor of this kind. The upper side of the piston with piston b' , admission ports c' and delivery valve d' , correspond to the double-acting compressor of 5 Figures 1 and 2, as also the driving eccentric f' , with sliding block g' , and the comparatively slight driving shaft e' mounted on both sides in bearings (preferably ball bearings) h' . On the other hand, the piston 10 ton is arranged differently on the opposite side, inasmuch as the guide bar for the block g' is formed on this side, as a circular guide disc i' , and the body of the piston above this is cut through. The guide disc i' is provided 15 with openings j' . The lower portion of the cylinder serves as an oil reservoir, in which the oil lies up to about the lower edge of the bearing h' . When running, the disc i' displaces the underlying oil at each down- 20 stroke, this oil spouting up through the openings j' into the interior of the piston and against the eccentric sliding block and the bearing h' , and also penetrates, in sufficient amount, to the upper side of the piston. 25 What I do claim as my invention and desire to secure by Letters Patent of the United States is:—
1. A compressor including a tubular casing, a piston reciprocating in the casing having a pair of spaced heads, one of said heads being imperforate, a slide block mounted on the piston between the heads, an eccentric engaging the slide block, means for rotating the eccentric to reciprocate the piston, the 30 path of the slide block being substantially within the plane of the path of the piston heads, and inlet and outlet apertures in the casing for the fluid being pumped. 35 2. A compressor including a tubular casing, a piston reciprocating in the casing having a pair of spaced heads, one of said heads being imperforate, a slide block mounted on the piston between the heads, an eccentric engaging the slide block, means for rotating the eccentric to reciprocate the piston, 40 the path of the slide block being substantially within the plane of the path of the piston heads, and inlet and outlet apertures in the casing for the fluid being pumped, the inlet apertures being located in the side walls 45 of the casing in position to be uncovered by the piston as it approaches its innermost position. 50 3. A compressor or the like comprising a cylinder and piston wherein the guiding end or face of the piston is provided with openings and the corresponding side of the cylinder is shaped as an oil well, so that lubricating oil is caused to spurt through the said openings into the interior of the piston 55 and to the working parts thereof. 60 In testimony whereof I have affixed my signature in presence of two witnesses.

WILHELM GENSECKE. [L.S.]
